UNITED STATES PATENT OFFICE.

JOHN C. FRANK, OF AKRON, OHIO.

DISK-RECORD HOLDER.

1,082,018.

Specification of Letters Patent. Patented Dec. 23, 1913.

Application filed January 31, 1913. Serial No. 745,442.

To all whom it may concern:

Be it known that I, JOHN C. FRANK, a citizen of the United States, residing at Akron, in the county of Summit and State of Ohio, have invented certain new and useful Improvements in Disk-Record Holders, of which the following is a specification.

My invention relates to graphophone disk record holders.

10 An important object of this invention is to provide a holder of the above mentioned character, which is so constructed that a suitable number of graphophone disk records may be safely stored away in a compact 15 manner, with the minimum loss of space, and be quickly and easily moved into and out of their stored positions.

A further object of my invention is to provide a holder of the above mentioned 20 character, which is so constructed that a selected graphophone disk record may be quickly and easily removed from the same, without disturbing the adjacent record or records.

25 A further object of this invention is to provide a holder of the above mentioned character, which is so constructed that a selected graphophone disk record may be readily observed, before the same is 30 entirely removed from the holder.

A further object of my invention is to provide a holder of the above mentioned character, which will properly protect disk records from being scratched or otherwise 35 injured when not in use, which will occupy the minimum amount of space, will be cheap to manufacture and neat in appearance.

A further object of my invention is to provide novel means for preventing the 40 accidental removal at the same time of two or more disk record receiving pockets or envelopes.

Other objects and advantages of the invention will be apparent during the course 45 of the following description.

In the preferred embodiment of my invention, I provide an outer casing or binder, which may be formed of any suitable rigid material. This casing or binder preferably 50 has one vertical side thereof formed open, while all the other sides are closed. Mounted within this casing or binder is a suitable number of relatively stationary division leaves, which are suitably spaced from each 55 other at their inner ends and connected with the casing or binder, whereby the same

are not capable of moving longitudinally with relation thereto. At their outer ends these relatively stationary division leaves preferably extend for a short distance beyond the casing or binder. The division leaves are preferably flexible, the same being preferably formed of suitably stout paper, whereby they are comparatively thin. Freely longitudinally movably mounted between the relatively stationary division leaves, are disk record receiving pockets or envelopes, formed of flexible material, preferably of paper. These pockets or envelopes extend at their outer ends beyond the free or outer ends of the division leaves. Each pocket or envelop preferably has its upper and outer ends formed open and the inner and lower ends closed, which arrangement I have found renders it particularly 75 easy to handle the disk records. The flexibility of the pockets or envelopes and division leaves, renders it possible to easily observe the disk records, before the same are completely removed.

Owing to the compact arrangement of the several pockets or envelopes, the operator might accidentally take hold of the two adjacent side walls of two separate pockets or envelopes, and by so doing withdraw at the same time two pockets or envelopes from the holder. To overcome this disadvantage, I preferably have each pocket or envelop of a different color from the others or each alternate pocket or envelop of a different 85 color from the adjacent pocket or envelop. It is thus seen that the operator can tell at a glance, whether he has hold of the two side walls belonging to the same pocket or envelop, or the side walls belonging to adjacent different pockets or envelopes.

Each pocket or envelop is preferably constructed a little shorter than the diameter of the disk record placed therein, whereby the disk record will extend at its outer edge 100 a little way beyond the side walls of the pocket or envelop, to be engaged by the thumb or finger of the operator, when forcing the envelop and record back in place. By this construction a saving in wear is 105 had upon the pocket or envelop.

The invention further consists in the novel combination and arrangement of the parts or elements thereof, as set forth in the annexed claims.

In the accompanying drawings, forming a part of this specification, and in which like

5 numerals are employed to designate like parts throughout the same, Figure 1 is a side view of the holder complete, the disk record receiving pockets or envelops being shown in their inner position and the cap or cover being removed, Fig. 2 is a central horizontal sectional view through the same, and Fig. 3 is a side view of the division leaves removed from the binder, showing a disk record receiving pocket or envelop partly removed from between the division leaves.

10 In the drawings, wherein for the sake of illustration, I have shown a preferred embodiment of my invention, the numeral 4 designates an outer casing or binder, which may be formed of any suitable rigid material, such as stiff cardboard, or thin sheets of wood. The binder 4 has one vertical side thereof formed open and all of the other sides closed, as shown. The binder 4 is provided adjacent the open vertical side with a reduced or contracted portion 5, for receiving thereon a removable cap or cover 6, as shown. Disposed within the outer casing or binder 4 is a suitable number of spaced division leaves 7, which are preferably permanently held against longitudinal movement with relation to the binder. These division leaves are suitably spaced, to provide 20 openings or spaces therebetween of substantially the same thickness as the combined thickness of the disk records and disk record receiving pockets or envelops, to be described. At their inner ends, the division leaves 7 have spacing strips 8 disposed therebetween, connected with the same by any suitable means, such as by gluing or the like. If necessary the spacing strips 8 may be connected by nails or pins driven therethrough. The spacing strips 8 may be secured to the binder 4, by any suitable means, such as by gluing the outermost division leaves 7 adjacent the spacing strips, to the inner side walls of the binder. Any other 30 suitable means however may be employed for this purpose. The division leaves 7 are preferably flexible and are preferably formed of paper, owing to the strength, flexibility and thinness of such material. At their outer ends, the division leaves 7 extend for a short distance beyond the binder 4, their upper and lower corners being preferably beveled, as shown at 9.

35 Longitudinally movably mounted between the division leaves, are disk record receiving pockets or envelops 10, which preferably have their upper and outer edges formed entirely open while the inner and lower edges are formed entirely closed. These disk receiving pockets or envelops are formed of flexible material, and I preferably construct them of paper, owing to the strength, flexibility and thinness of this material. Each disk receiving pocket or envelop 10 is 45 slightly longitudinally shorter than the di-

50 ameter of the disk record 11, disposed therein, whereby the forward edge of the disk record extends for a short distance outwardly beyond the outer open edge of the pocket or envelop. The operator can, by this construction, engage the disk record 11 with his thumb or finger to force the same and the pocket or envelop to the inner position. At their outer edges, the disk receiving pockets or envelops 10 extend, when in their innermost position, for a little distance beyond the division leaves 7, as shown. It is thus seen that by drawing a selected pocket or envelop 7 outwardly for a little way, one flexible side wall thereof may be bent laterally, as clearly indicated in Fig. 3, whereby the disk record may be seen. This also enables the operator to take hold of the disk record and to remove the same without completely removing the pocket or envelop, 55 such pocket or envelop serving to mark the place of insertion of the disk record.

60 Owing to the compact arrangement of the division leaves and disk record receiving pockets or envelops, it is obvious that the operator might accidentally take hold of two adjacent side walls belonging to different pockets or envelops, whereby he would accidentally draw out at the same time these pockets or envelops. To prevent this I have 65 each pocket of a color different from that of the adjacent pocket. I prefer to make these pockets or envelops in solid colors, that is one will be red, another green, and another yellow, etc. It is thus seen that if 70 the operator should take hold of two adjacent side walls having different colors, he would know at once that he was about to draw out two separate pockets. It is of course not necessary that each pocket or envelop should be of a different color from 75 each other pocket or envelop, it being sufficient that the alternate pockets are of different colors.

80 In the use of the holder the disk records 11 are placed within the pockets or envelops 10, which are freely longitudinally movably mounted between the partition leaves 7. The partition leaves 7 prevent one pocket or envelop from moving the adjacent pocket 115 or envelop, when the former is moved. When all of the pockets or envelops are filled with disk records, it is obvious that such disk records will be firmly held in the proper place. With this in view, I fill any 120 of the envelops or pockets, not holding disk records, with dummy records, in the form of a piece of card-board (not shown) of the same thickness as the disk records.

125 It is to be understood that the form of my invention herewith shown and described, is to be taken as a preferred example of the same, and that certain changes in the shape, size and arrangement of parts may be resorted to without departing from 130

the spirit of the invention or the scope of the subjoined claims.

Having thus fully described my invention, I claim:—

5. 1. A disk record holder of the character described, comprising a binder, division leaves disposed therein and held against longitudinal movement with relation thereto, and disk record receiving pockets formed 10 of flexible material and having their outer edges open and longitudinally movably mounted between the division leaves.
15. 2. A disk record holder of the character described, comprising a binder, and a plurality of disk record receiving pockets longitudinally movably mounted within the binder, each pocket being slightly shorter in its longitudinal dimension than the diameter of the disk record held thereby, and extending 20 for a considerable distance, when in its innermost position, outwardly of the binder.
3. A disk record holder of the character described, comprising a binder, a plurality of relatively stationary flexible division 25 leaves mounted therein with their free ends extending for a considerable distance beyond the binder, and a plurality of different colored longitudinally movable disk record receiving pockets disposed within the 30 binder between the division leaves.
4. A disk record holder of the character described, comprising a binder, a plurality of spaced stationary division leaves mounted therein, and a plurality of longitudinally 35 movable disk record receiving pockets mounted between the division leaves and formed of different colored paper.

In testimony whereof I affix my signature in presence of two witnesses.

JOHN C. FRANK.
